Primary Examiner — Jennifer L Watkins(74) *Attorney, Agent, or Firm* — Patterson Intellectual Property Law, P.C.; Jerry Turner Sewell(57) **CLAIM**

The ornamental design for a “back brace with heating and vibration,” as shown and described.

DESCRIPTION

FIG. 1 is a front perspective view of a back brace with heating and vibration in a closed position showing our new design.

FIG. 2 is a rear perspective view thereof;

FIG. 3 is a front perspective view thereof in a flat position;

FIG. 4 is a rear perspective view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a left side elevation view thereof; and,

FIG. 10 is a right side elevation view thereof.

In the figures, the evenly dashed broken lines depict portions of a back brace with heating and vibration that form no part of the claim. The dash-dot-dash lines depict the claim boundary and form no part of the claim.
